UNITED STATES PATENT OFFICE.

ARON RAUCH, OF NEW YORK, N. Y.

BOTTLE-CLOSURE DEVICE.

1,098,758.

Specification of Letters Patent.

Patented June 2, 1914.

Application filed September 23, 1913. Serial No. 791,279.

To all whom it may concern:

Be it known that I, ARON RAUCH, a citizen of the United States, and residing at New York, in the county of New York and State of New York, have invented certain new and useful Improvements in Bottle-Closure Devices, of which the following is a specification, such as will enable those skilled in the art to which it appertains to make and use the same.

This invention relates to closure devices for bottles and other vessels used as containers for hair tonics, perfumes, and other liquid substances used by barbers, hair dressers, and others; and the object thereof is to provide an improved closure device for bottles or vessels of this class whereby small quantities of the contents of the bottle may be discharged whenever desired, and whereby the bottle or vessel when emptied, cannot be refilled or reused without destroying the closure device.

This invention is fully disclosed in the following specification of which the accompanying drawing forms a part, in which the separate parts of my improvement are designated by suitable reference characters in each of the views, and in which;

Figure 1 is a view partly in section showing a bottle provided with my improved closure device, and showing said bottle as in the operation of discharging a portion of the contents thereof, a part of the closure device being removed, and Fig. 2 a view showing the bottle in an upright position and showing the closure device complete.

In the practice of my invention, as shown in the drawing, I provide a bottom *a* having a neck *a*² provided, in the form of construction shown with an annular bead or enlargement *a*³, and in the practice of my invention, I provide a closure cap *b* comprising an inverted thimble-shaped portion *b*² having an annular base *b*³ adapted to be clamped around and secured to the annular bead or enlargement *a*³ of the neck of the bottle, and the part *b*² is composed of soft flexible metal or other suitable material, and placed within the base of the cap *b* is a packing disk 50 or gasket *c*.

The closed end of the thimble-shaped part *b*² of the cap *b* is provided with a central aperture *b*⁴, and said end is also preferably reduced in size and threaded and provided 55 with a correspondingly threaded and removable cap *d* having a central pin *d*² adapt-

ed to be passed down through the aperture *b*⁴. The lower end of the thimble-shaped part *b*² of the cap *b* is also provided, in the form of construction shown, with an interior thread 60 *b*⁵, and screwed thereinto is a tubular plug *e* on the top of which is placed a valve *f* having a stem *f*² which passes downwardly through said tubular plug and is preferably provided at its lower end with a weight *f*³ 65 which is preferably detachable, or the valve *f* may be detachable from the stem *f*², if desired.

In practice, the bottle is first filled with the desired contents after which the plug *e*, 70 with the valve *f*, its stem *f*² and weight *f*³ is screwed into the thimble-shaped portion *b*² and the cap *d* is screwed into position on said thimble-shaped portion in which operation the pin *d*² passes around through the aperture *b*⁴ and rests on the valve *f*, or approximately so, after which the closure cap is secured on the neck of the bottle in the manner of other devices of this class.

Whenever it is desired to discharge a 80 part of the contents of the bottle, the cap *d* is removed and the bottle is inverted or tilted, as shown in Fig. 1, and agitated in a vertical direction, and the longitudinal movement of the valve stem *f*² through the 85 plug *e*, and the corresponding movement of the weight *f*³ will permit small quantities of the contents of the bottle to flow out through the cap or closure device, and this operation may be continued, or repeated until the bottle is entirely emptied, or partially so.

In the use of bottles of this class, as heretofore constructed, after the bottle has been emptied, or partially so, it has been customary with unprincipled dealers or operators, to refill the bottle with a counterfeit liquid by inserting the end of the nozzle of an oiling can or similar receptacle, filled with the counterfeit liquid, into the aperture *b*⁴, and by manipulating the bottom of said can by pressure alternately applied and removed therefrom, forcing the liquid from said receptacle, into the bottle, but with my improvement, the chief feature of which is the valve *f* movable longitudinally of the closure device and adapted to close the passage through the plug *e*, no liquids can in this manner, be forced into the bottle, and said bottle cannot be refilled or reused.

The length of the valve stem *f*² is such that when the bottle is inverted, as shown in

Fig. 1, the valve f will not rest on the end of the thimble-shaped part b^2 of the cap b , but my invention is not limited to the use of the weight f^3 , nor to the use of the pin d^2 on the detachable cap d , but I preferably employ these elements of construction for the reason that they facilitate the operation of the device as described.

In the form of construction shown, the 10 valve f is conical in form and provided with an annular enlargement, and the valve seat in the plug e is also conical in form, but my invention is also not limited to this form of construction and any suitable valve device 15 may be employed. It will also be understood that the tubular plug f is not an essential feature, and the bottom of the thimble-shaped portion b^2 of the cap b may be provided in any way with a reduced tubular 20 passage.

Having fully described my invention what I claim as new and desire to secure by Letters Patent is:—

1. A closure device for bottles or vessels 25 of the class described provided with a neck at the top of which is an annular bead, said closure device comprising an inverted thimble-shaped portion having an enlarged base of flexible material adapted to be secured on 30 said neck and around said bead, and a packing placed between the top of the neck and the thimble-shaped portion of the closure device, the upper end of the thimble-shaped portion being also provided with a central 35 aperture, and the bottom part thereof being provided with a reduced longitudinal passage, a valve mounted in the top of the thimble-shaped portion and adapted to close said 40 passage and provided with a stem which passes downwardly and loosely therethrough

and is movable longitudinally therethrough, and a removable cap mounted on the top of said thimble-shaped portion and provided with a pin which passes downwardly through the aperture therein and is adapted 45 to hold said valve seated.

2. A closure device for bottles or vessels of the class described provided with a neck at the top of which is an annular bead, said closure device comprising an inverted thimble-shaped portion having an enlarged base of flexible material adapted to be secured on said neck and around said bead, and a packing placed between the top of the neck and the thimble-shaped portion of the closure device, the upper end of the thimble-shaped portion being also provided with a central aperture, and the bottom part thereof being provided with a reduced longitudinal passage, a valve mounted in the top of the thimble-shaped portion and adapted to close said passage and provided with a stem which passes downwardly and loosely therethrough and is movable longitudinally therethrough, and a removable cap mounted on the top of said thimble-shaped portion and provided with a pin which passes downwardly through the aperture therein and is adapted 50 to hold said valve seated. 55

In testimony that I claim the foregoing as my invention I have signed my name in presence of the subscribing witnesses this 22nd day of September, 1913.

ARON RAUCH.
